UNITED STATES PATENT OFFICE.

GILBERT A. CASSAGNES, OF PARIS, FRANCE.

PRINTING-TELEGRAPH.

SPECIFICATION forming part of Letters Patent No. 313,176, dated March 3, 1885.

Application filed May 10, 1884. (No model.) Patented in France April 7, 1884, No. 161,395.

To all whom it may concern:

Be it known that I, GILBERT ALFRED CASSAGNES, civil engineer, of Paris, in the Republic of France, have invented an Apparatus for the Automatic Transcription of Stenographic Signs and Characters into Typographical Characters, (for which I have obtained Letters Patent of France for fifteen years, dated April 7, 1884, and numbered 161,395;) and 10 I do hereby declare that the following is a full and exact description thereof, reference being made to the accompanying drawings.

In two previous applications, the one filed October 25, 1883, known as Serial No. 109,934, 15 and since patented—to wit, on November 11, 1884—the other filed May 9, 1884, known as Serial No. 130,852, both of which concern the application to the uses of telegraphy of the principles of mechanical stenography, and es- 20 pecially those known and patented under the name of "Michela's system of mechanical stenography," I have shown different methods of attaining the object I had in view—namely, the transmission at a distance of signs or letters representing the phonetic sounds.

In my two said applications a printed band or tape is described, the same as the band or tape produced by the stenographic machine itself. Although this printed band or tape is 25 sufficient for many objects, it nevertheless renders the assistance of persons having a perfect knowledge of the reading of stenographic characters necessary; hence a larger number of skilled persons and more time will be re- 30 quired to execute the work. I therefore believe that a system of automatic transcription of the signs or characters of stenography into ordinary letters of the alphabet would be 35 highly advantageous. It would facilitate the reading, would diminish the time required for it, and would render the employment of skilled persons for the purpose of transcribing the printed bands at the receiving-station useless.

The object of my present invention is, therefore, in a general manner, the automatic transcription of bands of paper bearing stenographic characters by a system of machinery fitted with key-boards.

I will now proceed to describe my invention, but shall first observe that this automatic

transcription, while it presents evident advantages, such as those I have just enumerated, does not detract from the value of the stenographic system which is described in my former applications.

In the accompanying drawings, Figure 1 represents a side elevation, partly in section, of my improved machine. Fig. 2 is a top view of the same. Figs. 3, 4, 5, 6, 7, and 8 are diagrams hereinafter referred to. Fig. 9 60 is a diagram illustrating the position and connections of the conducting-wires. Fig. 10 is a side view, on an enlarged scale, of the relay employed in the machine; Fig. 11, a face view, and Fig. 12 a top view, of the same.

The transmission, as shown in Figs. 1 and 2, is effected in the same manner as described in the two above-mentioned applications—namely, by means of a key-board whose keys K, when depressed, make contacts at the 70 transmitting-station T with electro-magnets, (not shown,) thereby closing the circuits through which the signal is transmitted to the receiving-station R.

The printing apparatus in the present case, 75 although different with respect to the number and nature of the letters or characters with which it is provided, can also, if wanted, be constructed in a similar fashion to that of the two printing systems I have previously de- 80 scribed in said earlier applications; but my present invention adds to those two essential parts of my system a third element—namely, the one wanted for the automatic transcription of the paper band or tape, and which I 85 call the "combiner." This combiner is placed at the receiving-station R, as shown at Y, Figs. 1 and 2; and its object is to receive the transmitted signals and to combine them one with the other, so as to cause the printing apparatus to reproduce the letter or letters corresponding to the signals or combinations of signals transmitted.

The combiner Y, which I shall now describe, can be applied to the automatic transcription of any stenographic band mechanically produced by the action of a key-board; but, for the sake of making it clearer, I will show its application to Michela's stenographic system, which I had more especially in view. 100

It is understood that in case another code or alphabet should be used, the combiner could be easily adapted to the same.

In order to make clearer the action of my 5 combiner, it may be useful that I should briefly recall the stenographic method in question.

Michela's key-board consists of twenty keys, divided from the left-hand side into four series, comprising, respectively, and in the following order from left to right, six, four, four, and six keys. The six keys in the first series form twenty-six combinations, corresponding to twenty-six letters, and these combinations 10 are the following: six combinations of one key at a time, twelve combinations of two keys at a time, and eight combinations of three keys at a time. In Michela's method there are never depressed more than three keys 15 at a time in each series. Of course, these twenty-six combinations do not represent the total number of possible combinations; but they are sufficient for the purpose of this method. The four keys of the second series 20 form eleven combinations, which are four combinations of one key at a time, five combinations of two keys at a time, and two combinations of three keys at a time. The third and fourth series are identical with the second 25 and first, respectively, the key-board being perfectly symmetrical on each side of the center line. From the left-hand side the six keys in the first series are numbered 1, 2, 3, 6, 9, and 18, respectively. Those of the second series 30 are numbered 1, 2, 3, and 6. From the center line the four keys in the third series are represented by the numbers 6, 3, 2, and 1; those of the fourth series by the numbers 18, 9, 6, 3, 2, and 1. Those keys combine as follows: 35

40 For the first series, (a.) Combinations of one key at a time, 1, 2, 3, 6, 9, 18. Total, 6. (b.) Combinations of two keys at a time, (1 3), (1 6), (1 9), (1 18), (2 3), (2 6), (2 9), (2 18), (3 9), (3 18), (6 9), (6 18). Total, 12. (c.) Combinations of three keys at a time, (1 3 9), (1 6 9), (1 3 18), (1 6 18), (2 3 9), (2 6 9), (2 3 18), (2 6 18). Total, 8. General total, 26. (Shown on the left-hand side of Fig. 8.)

The combination of the keys in the second 50 series are the following: (a.) Combinations of one key at a time, 1, 2, 3, 6. Total, 4. (b.) Combinations of two keys at a time, (1 3), (1 6), (2 3), (2 6), (3 6). Total, 5. (c.) Combinations of three keys at a time, (1 3 6), (2 3 6). Total, 2. General total, 11. (Shown on the right-hand side of Fig. 8.)

The key-board, as it has already been stated, being perfectly symmetrical, the combinations of the third and fourth series are identical 60 with those of the second and first series, respectively. It follows that the total number of necessary combinations to the application of the method is seventy-four, transmitted to the receiving-station and transformed by the 65 action of the combiner into seventy-four letters, which are printed by the apparatus on the paper band or tape.

I will now give a detailed description of the combiner. The currents closed by the contacts under the keys K of the transmitting 70 key-board, when they reach the receiving-station R, flow through electro-magnets placed at the points marked 1, 2, ... 18; 1, 2, ... 6; 6 . . . . . 1; 18 . . . . . 1, on Figs. 2 and 8. These currents, when they 75 are produced by the depression of a single key, pass directly through the combiner, as through an ordinary relay, so as to put in motion the style, P being the corresponding letter. When two simultaneous currents arrive 80 in the same series, through the simultaneous depression of two keys belonging to the same series at the transmitting-station, they move two relays of the combiner, and these two relays close only one local circuit, which, therefore, acts only on one printing-style P corresponding to the combination transmitted by the two keys depressed simultaneously. When three simultaneous currents arrive at the combiner in the same series, the combiner closes 85 only one local circuit, putting in motion the letter-printing style P corresponding to the combination transmitted by the three keys simultaneously depressed. It is also necessary that any combination of two currents corresponding to two depressed keys should break automatically in the combiner the local circuits of each one of these two keys taken singly. In the same manner, any combination of three keys should break, also automatically, 90 the local circuits of each one of these keys taken one at a time, as well as the local circuits of these keys taken two at a time.

As stated, Michela's key-board consists of four series of keys, and any number of keys 95 from one to three can be simultaneously depressed in each series. The combinations of signs produced represent for each series a single letter of the ordinary alphabet. It is therefore necessary for the automatic transcription of such a letter that only the combination representing it should act on the printing-instrument. This combination is necessarily that formed by the maximum number of keys depressed. For instance, when 105 three keys are depressed in one of the series this combination of three keys represent only one letter. This letter is printed, but unless means were provided the instrument would also print the letters represented by each key 110 taken singly, or by any combinations they form two at a time.

The means employed are clearly set forth in the description of Fig. 8, and consist in automatic circuit-breakers acting as follows: 125 When two keys are depressed, the circuits of each one taken singly are broken, and the common circuit of both taken together is left to act alone. Similarly, when three keys are depressed, the circuits of each one taken separately, as well as the circuits of the keys taken 130 two at a time, are automatically broken, and the common circuit of the three keys taken together is left to act alone.

I will now describe the principle of the local circuits of the various combinations of one, two, and three keys, respectively.

For the combination of one single key depressed at a time, the current of the line L, Fig. 3, flows through the electro-magnet of the relay E, attracts the armature A, which closes the local circuit of battery B, whose current then flows through the electro-magnet, which moves the letter-printing style P corresponding to the key depressed at the transmitting-station.

For the combination of two keys depressed at a time, the typical circuit can be represented by Fig. 4, which represents only the local circuit. When two currents arriving from the transmitting-station attract, by means of electro-magnets and armatures, the two contact-plates 1 and 2 on the contact-points placed underneath, the circuit of the local battery B is closed, and the letter-printing style P corresponding to the combination (1 2) is lifted by its electro-magnet. It is evident from the figure that this action can only take place when both the contact-plates 1 and 2 are simultaneously attracted. Similarly, for the combinations of three keys depressed at a time the typical local circuit is represented by Fig. 5. When the three contact-plates 1, 2, and 3 are simultaneously attracted by the action of three currents from the transmitting-station on the contact-points placed underneath, then, and then only, the circuit of the local battery B is completely closed, and acts on the letter-printing style P corresponding to the combination (1 2 3).

Fig. 4 represents only the local circuit for two keys depressed at a time. At 1 and 2 are two relays moved by currents coming from the line. (Not shown on the figure.) When the keys corresponding are depressed at the transmitting-station, these armatures pressed down the contact-plates represented by the two circles onto the contact-points connected with the conductors of the local circuit. It is easily seen from the figure that the local circuit is continuous only when both armatures are depressed; therefore the printing style at P corresponding to the combination (1 2) can only act when both keys are depressed.

Fig. 5 gives the diagrammatic typical local circuit for combinations of three keys depressed at a time. Here also the local circuit only is illustrated, and relays moved by the line-currents are placed at the points marked 1 2 3. When they are all three acted upon simultaneously, the circuit represented by the triangle 1 2 3 is continuous, and the battery B will send a current through the printing-style P corresponding to the said combination (1 2 3.) It is also seen that this action can only take place when all three contact-plates are pressed onto the contact-points placed underneath.

It is easy to see, from the examination of Fig. 8, how the circuits of the combinations of one key and of two keys are arranged. The

circuits of one key at a time are represented by the dotted lines; those of two keys by the chain-lines or dash-and-dot lines, and those of three keys by the continuous or full lines. I will exemplify with more details, by means of the diagrams or Figs. 6 and 7, the manner of arranging the circuits of the combination of three keys at a time.

Fig. 6 represents the local circuits of these combinations for the first and fourth series of the key-boards taken three at a time. (Eight combinations.) Each combination can be represented by a triangle.

Fig. 6 contains eight such triangles, corresponding to the eight combinations of the first and fourth series. The simultaneous attraction of any three contact-plates H closes, therefore, the local circuit of one of those eight combinations in attracting the vertices of the triangle by which it is represented. In order, however, that the attraction of the contact-plates H—at the angles marked 1, 18, and 3, for instance—which causes the flow of a current through the electro-magnet of the letter-printing style P, should not at the same time also cause the flow of a current through the electro-magnet of the letter-printing style P', which corresponds to the combination (1 3 9,) which would take place if the contact plates or rings were continuous, as P' is also connected with 1 and 3, it is necessary to make the said plates each in two pieces that are insulated from one another, as shown on the figure. The letter-printing style P' (1 3 9) can no more, then, be moved at the same time with the style P, (1 3 18,) and only acts when its section of the contact plate or ring 9 is attracted in unison with 1 and 3. This diagram indicates, therefore, the solution of the question—namely, to cause to flow through the electro-magnet of a letter-printing style, and through it alone, a current which moves it when the three keys corresponding to that style have been depressed at the transmitting-station.

Fig. 7 gives the solution of the question for the series 2 and 3 of the key-board. It will be easily understood on mere examination after the explanation which has just been given of Fig. 6.

Fig. 8 shows the general disposition of all the combinations for the fourth series of the key-board. As far as the combinations of three keys at a time are concerned, it is after all but the development of the diagrams of Figs. 6 and 7. Fig. 8 also indicates the most advantageous disposition concerning the economy in the number of batteries, &c. The series P P P ---- stand for the letter-printing styles, which are moved by electro-magnets. The batteries B B B ---- feed the local circuits of the combinations of three keys at a time. The batteries B' B' feed the local circuits of the combinations of one key and two keys at a time.

As I have already stated, it is necessary when one combination of two keys is transmitted that the local circuits corresponding to

each one of those keys, taken singly, should be broken at the receiving-station in order that the local circuit corresponding to the two keys taken at a time should act alone. It is also necessary for the combination of three keys that the local circuits of each one taken singly, as well as those of the combinations of two at a time, which they can form among themselves, should be also broken, so as to leave only the local circuit corresponding to the combination of the three keys at a time. I get at this result by means of the automatic disposition shown on Fig. 8. The electro-magnets $E^o E^o E^o E^o$ of the relays are placed in the local circuits of the combinations of two keys at a time, which circuits are represented by the chain-lines or dash-and-dot lines. These electro-magnets are wound with two wires in order to avoid having two separate electro-magnets together with twice the number of armatures. When one of those wires is traversed by an electric current, both armatures are attracted, and the circuits of the keys, taken one at a time, which circuits are represented by the dotted lines, are thereby automatically broken. Similarly, when the interrupting electro-magnets $E' E' E' E'$, traversed by the continuous lines representing the local circuits of the combinations of three keys at a time, are magnetized by the passage of an electric current in one of those wires, they will attract their armatures, and will break automatically the circuits of the combinations of one at a time and of two at a time.

It will be noticed on examining Fig. 8 that the local circuits of the combinations of three keys at a time are interrupted in $a b c d e f g h$, and that the same letters are shown on the wires traversing the electro-magnets $E' E' E' E'$ on the lower part of the figure. In reality these circuits are continuous, and the above-mentioned electro-magnets are included in them; but for the sake of making the drawing clearer, I have thought it more advisable to place those electro-magnets lower down, after, however, having given the present explanation. My combiner, such as it is diagrammatically represented on Fig. 8, gives, therefore, a complete solution of the question of the automatic transcription of Michelâ's band into ordinary characters; and, as this method of stenography can be applied to all languages, it follows, therefore, that my invention allows the transcription of mechanical stenography into ordinary characters for the various countries where my apparatus would be employed. However, I only intend to give the combiner I have just described as an example, in order that the method of automatic transcription of bands produced by mechanical stenography be better understood; and although I claim the property of this combiner, I mean, however, to keep the right of introducing such modifications as I may deem advisable.

In my preceding application of May 9, 1884, I have already stated, as far as Michela's

method is concerned, and by making use of the same wire or conductor for two keys, that I could reduce to twelve instead of twenty the 70 wires or conductors of my electric cable, not counting the return-wire.

By examining the combinations I have given at the beginning of this specification it will be noticed that for the first and fourth series of Michela's key-board, key No. 1 forms no combination with key No. 2, nor key No. 3 with key No. 6, nor key No. 9 with key No. 18. I can therefore use only three wires or conductors for each one of these two series by making use of polarized relays and currents of different directions. The second and third series will each want three wires or conductors. Key No. 1 enters into no combination with key No. 2. The total number of requisite wires or conductors is therefore twelve.

The method of connection I have just shown has also the valuable advantage of automatically stopping the transmission of any erroneous signals. For instance, if, through any mistake on the part of the manipulator, keys No. 1 and No. 2 were depressed at the same time, no current would pass through the line, for one of the keys would tend to transmit a current in the positive direction and the other in the negative direction. 95

Fig. 9 shows the method of having only twelve line-wires instead of twenty. K K K - - - (numbered 1 2 3 - - - 19 20) are the twenty keys of the manipulator, provided with electrical contact-pieces, so as to close the circuits on which they are placed when they are depressed. B B' are two batteries, connected with these keys (ten keys each) by their opposite poles. L L is a line-cable connecting both stations. R R R - - - are polarized relays, worked only by currents flowing in definite directions. r r r - - - are ordinary relays. According to Michela's alphabet keys 1 and 2 are never depressed simultaneously, nor are keys 3 and 4, 5 and 6, 7 and 8, 13 and 14, 15 and 16, 17 and 18, 19 and 20. Therefore, if key No. 1 is connected with battery B and key No. 2 to battery B', the first will send positive and the second negative currents through the line. They can therefore have only one line wire or conductor for both of them between the two stations. At the receiving-station the polarized relay R_1 will be acted upon if the current is positive, and the polarized relay R_2 if the current is negative. The action of the other relays will be similar. It is easily understood how the polarized relays R R R - - - on one hand and the ordinary relays r r r - - - on the other can, in their turn, close local circuits corresponding to the twenty relays of the combiner without its being necessary to show the arrangements on the diagram. This mode of making the connections has also the further advantage of preventing the transmission of erroneous signals, for if keys No. 1 and No. 2, for instance, were erroneously depressed at the same time, (a

would tend to transmit a positive current and key No. 2 a negative current through the same wire. These two actions would mutually destroy one another, and no current would flow 5 through the line L corresponding to these two keys 1 and 2. The other keys would not either send any current at this instant, as the two batteries B and B' would be short-circuited, and therefore no erroneous or incomplete signal could be transmitted. This reduction of the line-wires to twelve instead of twenty is not, however, a minimum. By means 10 of synchronously rotating disks or tables of contacts, as already alluded to, only one wire need be used. These instruments are too well 15 known in multiplex telegraphy to need description.

The printing part of my apparatus can be constructed according to the same principle 20 as those I have already described in my previous applications, but with seventy-four printing-styles bearing ordinary letters in the case of Michela's method, or with a number of styles corresponding to the number of combinations in the signal-code made use of. As 25 for the disposition of my seventy-four letter-printing styles, it can naturally be very changeable. They can be arranged on several rows and close to one another, and be acted on directly by electro-magnets placed in like rows. This is the disposition shown on Figs. 1 and 30 2. The printing can then be effected by the style itself pressing on an inking-ribbon. The forward motion of the paper can also be effected, as shown in my previous applications, 35 with paper bands having a width corresponding to the width of the arrangement of the styles, and the printing can then be done in syllabic lines placed one underneath the other. It can 40 also be done by placing the mechanism producing the motion of the paper at right angles to the preceding position, which would necessitate a paper band of a much smaller width, and would place the syllables one after 45 the other in a continuous line. In this case the paper band could have the width and the appearance of the paper band of Hughes's printing-telegraph, for instance, but the letters would be neither side by side nor between 50 two parallels. They would be placed at variable heights on the width of the paper band.

I have given an illustration of one of the multiple contacts and independent circuit-relays shown at 1 2 3, &c., Fig. 8. This relay is shown on a larger scale in Figs. 10, 11, and 55 12, and will help to the better understanding of the action of this important part of my apparatus. It consists of an electro-magnet, A², with two coils having their terminals at B³ B⁴; a soft-iron armature, C, fixed on the frame 60 D, which is movable round the pins E³ E⁴. A spring, F, draws back the armature C after attraction.

On the front part of the movable frame D is an ebonite piece, G, on which are fixed two 65 brass contact-bars, H H. The contact-springs I I I ----- rest on the ebonite piece G when the armature is raised. When a current from the line flows through the coils of the electro-magnet A², its armature C is attracted, and the 70 frame is moved down bodily, so that the extremities of the contact-springs I I I --- slide from the ebonite bar onto the contact-pieces H H, and are thereby put into electrical connection. The terminals K³ K³ K³ ----- serve to 75 connect the wires going to each contact-spring I.

I claim as my invention and desire to secure by Letters Patent—

1. The apparatus for the automatic and electrical transcriptions of conventional signs or combinations of signs forming a stenographic alphabet into ordinary letters, which apparatus embraces the combination of the keys K, line L, combiner Y, having printing electro-magnets and styles P, and batteries B B', all arranged substantially as herein shown and described. 80

2. The hereinbefore-described combiner Y, consisting of the conductors, printing electro-magnets, relays, circuit-breakers E³ and E', and styles P, substantially as described. 85

3. In combination with series of keys K K, conductors L L, and electro-magnets E E, the divided sectional contact-plates H, arranged 90 for joint operation in prearranged series, as specified. 95

G. A. CASSAGNES.
